PORTABLE EXERCISER

John H. Miller, Laconia, N. H., assignor to Scott & Williams, Incorporated, Laconia, N. H., a corporation of New Hampshire

Application March 15, 1951, Serial No. 215,744

24 Claims. (Cl. 128—33)

1

This invention involves a portable exerciser of a type adapted to be employed for the cyclic raising and lowering of a patient's leg in a manner generally known in the medical arts to have desirable effects in medical treatment by desirably effecting the circulation of the blood stream in the leg.

Heretofore there have been provided rocking beds for the purpose of raising and lowering a patient's leg in order to stimulate the blood circulation therethrough. The rocking beds heretofore employed rock the patient's body as well as the patient's leg. This motion of the patient's body frequently causes sea sickness or other discomfort to the patient.

The present exerciser is adapted to be positioned beside a bed in such a manner as to permit the patient's body to rest partly on the bed and partly on the exerciser while one of the patient's legs is being exercised. This motion of the patient's leg is accomplished without movement of the patient's body.

It is an object of this invention to provide a portable exerciser which may be attached to a bed in such a manner that the patient lying partly on the bed and partly on the exerciser will have one of his legs, which is resting on the exerciser, periodically elevated and depressed with individually predetermined periods of rest at the elevated, horizontal and depressed positions.

It is a further object of the invention to provide an exercising apparatus in which the periods of dwell of the patient's leg at an elevated position, at a horizontal position and at a depressed position may be adjusted to various time intervals as may be desired.

It is another object of this invention to provide an exerciser having separate portions adapted to support the patient's leg and the patient's heel which will move in relation to each other in such a manner upon being elevated and depressed as to avoid motion or scuffing of the patient's heel upon the heel supporting portion of the exerciser.

These and other objects of the invention will become apparent from the following description when read in conjunction with the accompanying drawings, in which:

Figure 1 is a perspective view of the exerciser; Figure 2 is an enlarged fragmentary view of the exerciser showing a portion of the mechanism for operating the leg and foot supporting members of the exerciser;

Figure 3 is a fragmentary showing of a por-

2

tion of the apparatus controlling the operation of the mechanism for elevating and depressing the leg and foot supporting members of the exerciser;

5 Figure 4 is a plan view of the apparatus shown in Figure 3;

Figure 5 is a diagrammatic showing of the electrical control circuit employed;

10 Figure 6 is a detailed showing of a portion of the electrical control apparatus employed;

Figure 7 is an enlarged showing of a fragmentary portion of Figure 2; and

Figure 8 is a sectional view taken on the trace 8—8 of Figure 7.

15 In Figure 2, platform members 44 and 50 are shown in solid lines in their normal horizontal position. They are shown at 44' and 50' in dash lines in an elevated position, and they are shown at 44'' and 50'' in construction lines in

20 a depressed position. The mechanism for positioning the platform members is similarly shown in solid lines, dash lines and construction lines in their various positions.

25 Mounted on the underside of the platform member 44 is a member 58 which is provided at its lower end with a forked and cut-out portion 60 for engagement with the pins 56 which are mounted to either side of the member 54. The member 58 prevents rotation of the driving member 54 and thus as the driving shaft 42 rotates and the member 54 travels inwardly or outwardly thereon, the platform member 44 will be raised or lowered as the member 58 is carried to an outward position, as shown at

30 58', or to an inward position as shown at 58''. As the platform member 44 moves about the hinge 43, the member 54 will travel in an arc and will assume various positions of elevation. By reference to Figure 1, it will be apparent that, as the member 54 assumes various positions of elevation, the motor mounting cradle 36 will swing on the pins 32, and thus the outer end of the drive shaft 42 will be free to move upwardly or downwardly as shown in Figure 2.

35 45 The exerciser comprises a framework of four horizontally extending members 2 which is mounted on four swivelling castors 4 and includes four vertically positioned tubular members 6. A framework of four horizontally extending members 8 is mounted on and provides rigidity to the vertical members 6.

40 45 Four tubular members 12 are mounted on and extend downwardly from a framework of four horizontally extending members 14. Each of the members 12 is adapted to slide downwardly

within one of the four vertical members 6. Mounted on the upper ends of the members 12 is a platform 16 which is covered with a suitable padded mattress or cushion 18 on which the patient will lie. A bumper pad 15 is affixed to the upper portion of each of the members 12.

A cross member 20 is mounted on two of the framework members 14 and supports a vertical rod member 22 which is threaded at its lower end, as indicated at 24, and passes freely through a cross member 26 which is mounted on two of the lower framework members 2. A hand wheel 28 is mounted on the threaded portion 24 of the vertical rod 22 above the cross member 26. The hub of the wheel 28 is in engagement with the member 26 and thus, by rotation of the wheel in one direction, the member 22 will be moved upwardly carrying with it the cross member 20, the framework 14 and the platform 16. If the wheel 28 is rotated in the opposite direction, the weight of the apparatus will force the screw 24 downwardly through the member 26, the tubular members 12 will move into the tubular member 6 and the bed will be lowered. The clamp screws 16 mounted in the tubular members 6 are provided to clamp the members 12 within the members 6 after the table has been adjusted to any desired height by operation of the hand wheel 28, and thus any rotation of the wheel 28 on the rod 22 resulting from vibration during the operation of the machine will not alter the height of the platforms.

A shaft 9 is rotatably mounted on two of the framework members 14 and may be manually rotated by a crank 11. A pair of straps 17 are mounted on drums on the shaft 9. Affixed to the ends of the straps 17 are hooks 19 which are adapted to be hooked to the frame of a hospital bed beside which the exerciser is placed when in use. A ratchet and detent arrangement 13 is provided to lock the shaft against rotation after the hooks 19 have been hooked to the bed frame and the straps wound on the drums by rotation of the crank 11 to hold the exerciser snugly against the bed. The pads 15 prevent scraping between the frame of the bed and the frame of the exerciser.

It will be apparent that the straps 17 may pass outwardly from the drums on the shaft 9 either across the top of the drum in the direction shown in Figure 1 in order to attach the exerciser to the right hand side of a hospital bed or, alternately, the straps 17 may pass outwardly from under the drums on the shaft 9 towards the opposite side of the exerciser from that shown in Figure 1, and thus provide for the attachment of the exerciser to the left hand side of a hospital bed.

Also mounted on two of the framework members 14 are a pair of members 30 retaining hinge pins 32 on which a cradle member 36 is mounted. Mounted on the cradle member 36 is a motor and speed reducer assembly 38 and extending from the speed reducer and supported by an extension 40 of the member 36 is a shaft 42 which rotates when the motor is in operation.

A platform 44 is hinged to the platform 16 by means of hinges 43, and is provided with a suitable cushion 46 to support the patient's thigh. Mounted to the underside of the platform 44 are a pair of channel members 48. These channel members are rigidly mounted to the member 44 adjacent to either side thereof with their flanges turned inwardly. The channels extend outwardly from the platform 44 and support a platform

50 which is movably mounted on the channel members by means of rollers 52 which are mounted on the underside of the platform member 50 and roll within the channel members 48. The platform 50 is provided with a suitable cushion 51 to support the patient's heel.

The movable platforms 44 and 50 and their respective cushions 46 and 51 are somewhat more narrow than the stationary platform 16 and its cushion 18. This arrangement provides a suitable clearance between the mattress of the bed to which the exerciser is attached and the movable platforms 44 and 50 of the exerciser to prevent wear on the bed mattress and covers which would otherwise result if the moving portions of the exerciser were to brush against the bed mattress and covers when the exerciser is in operation.

20 Mounted behind the shaft 42, in the region indicated generally by the arrow 41 in Figure 1, is a stroke control limit switch and cam assembly shown in detail in Figures 3 and 4 which will be hereinafter described.

The outer end of the shaft 42 is threaded, as indicated at 52, and mounted thereon is a threaded member 54 which mounts a pair of outwardly extending pins 56. The member 54 is prevented from rotating by structure to be described and as a result it will move longitudinally on the threaded member when the threaded member is rotated in one direction or the other as a result of operation of the motor 38. This longitudinal motion of the member 54 is employed to raise and lower the platforms 44 and 50 supporting the thigh and lower leg of the patient. The mechanism for raising and lowering the platforms is shown in detail in Figure 2 in which figure the cam and stroke controlling apparatus, shown in Figures 3 and 4, has been omitted so as not to unduly complicate the drawing.

45 The lower leg supporting platform 50 is movably mounted on the channels 48, and as the platform 44 is raised or lowered, the platform 50 is moved outwardly or inwardly on the channels by motion of a member 62. One end of the member 62 is pivotally attached to the platform 50 at 64, and the other end pivotally attached to the end 68 of a member 66. The other end 50 of the member 66 is pivotally attached to one end of a member 70 at 72. The other end of the member 70 is pivotally attached to a collar 74 as shown at 76. The member 74 is rigidly connected to the vertical rod member 22.

55 The member 66 is provided with a slot 78. A pin 80 is affixed to the lower portion of the member 58 and extends through the slot 78 as shown in Figure 2. A clamp nut 82, as shown in Figure 3, and its associated parts are provided to securely clamp the member 66 with respect to the pin 80 to prevent longitudinal motion of the slot 78 in the member 66 with respect to the pin 80 while permitting the member 66 to rotate freely about the pin 80.

60 The clamp nut 82 and its associated parts are shown in Figures 7 and 8. The member 58 is provided with an extended portion 301 in which the threaded pin 80 is mounted and held by means of a set screw 302. A sleeve 303, a serrated washer 304 and a key 305 are held together by means of two screws 306 and are positioned over the pivot pin 80 and retained thereon by the head 307 of the pivot pin 80. The member 66 has its surfaces adjacent to the slot 78 serrated and the washer 304 is provided with

matching serrations as indicated at 308. The outer end of the pivot sleeve 303 carries the threads 309 which are adapted to receive the clamp nut 82. The clamp nut 82, when threaded onto the pivot sleeve, is adapted to bear against the washer 310 and apply pressure holding the serrated portion of the member 66 in engagement with the serrated washer 304, thus preventing longitudinal motion of the member 66 with respect to the pin 80. The pivot sleeve 303 is, however, free to rotate on the pin 80 and thus, the member 66 is provided with free pivotal motion about the pin 80. Longitudinal motion of the member 66 with respect to the pin 80 is prevented when the clamp nut 82 is tightened on the pivot sleeve. However, when the clamp nut is loosened to permit the serrated surfaces of the member 66 and the washer 304 to slide past each other, the position of the pin 80 in the slot in the member 66 can be adjusted.

It will be observed that, with the platform members in their horizontal positions, as shown at 44 and 50, there is provided a space, indicated generally at 84, between these two platform members. When these members are displaced to an upward position, as shown at 44' and 50', the action of the pivotally connected members 62' and 66' is to increase the distance between the members 44' and 50' as shown generally at 84'. As the members 44' and 50' are moved downwardly to a lower position, the action of the pivotally connected members 62'' and 66'' is to reduce the space 84'' between the members 44'' and 50''.

This displacement of the member 50 inwardly and outwardly as the hinged platform is raised and lowered is highly desirable. A patient lying on the top of the stationary platform with his leg supported by the hinged platform will have his pelvic hinge displaced from the hinge 43 between the platforms. As a result of this displacement, the patient's heel will tend to move outwardly as the hinged platform moves upwardly, and the patient's heel will move inwardly as the hinged platforms move downwardly. Thus the movement of the platform 50 inwardly and outwardly as the platform 44 is lowered and raised prevents rubbing or scuffing of the patient's heel such as would otherwise occur on the platform 50.

By adjusting the position of the pin 80 in the slot 78 in the member 66, the degree of outward and inward motion of the platform 50 with respect to the platform 44 can be adjusted to accommodate the leg length and hinge displacement involved with any particular patient.

As previously stated, the raising and lowering of the leg supporting platform is accomplished by operating the motor 38 first in one direction and then in a reverse direction. The duration of operation or the number of revolutions of the motor from a zero or horizontal table position will determine the degree of elevation or the degree of depression of the leg supporting platform. In Figures 3 and 4 there is shown in enlarged 65 fragmentary form the portion of the drive shaft as viewed from the rear and top sides, respectively, in the region indicated generally by the arrow at 41 in Figure 1.

Rigidly mounted to the drive shaft supporting arm 40 is a limit switch mounting bracket 86 which mounts three limit switches 90, 92 and 94 which are held into position by means of a bracket 88. A control rod 96 is affixed to the outer end of one of the extending pins 56 of 75

the member 54 by means of a screw 98. The control rod is adapted to be moved as the member 54 moves backwardly and forwardly parallel to the rotating shaft. The limit switch mounting bracket 86 is provided with a turned-down flange portion 87 which serves to support the control rod 96 against the urging of the rollers 91, 93 and 95 of the limit switches 90, 92 and 94, respectively, which engage the control rod 96.

10 The control rod is provided in the center of its length with a notch 100. The slidably mounted bottom limit cam 104 is mounted adjacent to the outer end of the control rod and the slidably mounted top limit cam 108 is mounted adjacent to the inner end of the control rod. These limit cams are provided with the thumb screws 105 and 106, respectively, to lock the cams to the control rod in any position where they may be set. The limit switch 92 is held in a position with- 20 in the retainer 88 so that its roller 93 will enter the notch 100 in the control rod. The limit switch 94 is so positioned that its roller 95 will be pressed inwardly by the cam 104 when the control rod has moved to the left to an extreme 25 outer position by motion of the member 54. The limit switch 90 is so positioned that its roller 91 will be depressed upon engagement with the limit cam 108 when the control rod has moved to an extreme right hand or inner position as a 30 result of motion of the member 54 on the drive shaft 42. The limit switches 90, 92 and 94 contain switch contact arms 233, 231 and 235, respectively, which are connected into a control circuit, as will be hereinafter described, in such 35 a manner that operation of the bottom limit switch 94 upon engagement with the bottom limit cam 104 will stop the drive motor when it is driving the platforms in a downward direction. The top limit switch 90 upon engagement with 40 the top limit cam 108 will stop the drive motor when it is driving the platforms in an upward direction, and the level limit switch 92 upon en- 45 gagement of its roller 93 with the notch 100 with the control rod will stop the operation of the motor with the platforms at a horizontal position.

The control rod is calibrated, as shown at 102, in degrees starting with the zero degree marking at the notch 100 and increasing in either direction 50 away from the notch. The calibration marks on the control rod are scaled so that when the bottom limit cam is set at the 30° calibration the movable platforms of the exerciser will stop their downward motion at a 30° displacement from a horizontal position. When the top limit cam is set at the 30° position, as shown in Figure 3, upward motion of the movable platforms will be arrested at an angle of 30° above the horizontal position.

55 The limit stops 109 and 103 are rigidly fixed to the control rod 96 and serve to limit the maximum outward setting of the stop cams 108 and 104, respectively. If the stop cam set screws become loose, the limit stop will prevent the stop cams from sliding an excessive distance on the control rod.

At the extreme outer end of the drive shaft 42 there is provided a pair of jam nuts 110 which will serve to limit the upward motion of the table if the top limit control fails to operate. There is similarly provided a collar 112 at the inner end of the threaded portion 52 of the drive shaft 42 which will limit the downward motion of the platforms if the bottom limit control fails to operate.

The electrical apparatus contained within the box 114, as shown in Figure 1, is diagrammed in Figure 5. In Figure 5 there is shown the input power lines 115 which are connected through switch 116 and fuses 218 to the control circuit. The control circuit involves three timers, a top limit timer 120, an intermediate or level timer 122 and a bottom limit timer 124. Associated with each of the timers 120, 122 and 124 are the pilot lamps 121, 123 and 125, respectively. The pilot lamps and the control knobs for adjusting the timers, as will be hereinafter described, are shown extending through the cover of the box 114 in Figure 1. The control circuit also employs the start switch 156 which is exposed through the cover of the box 114 in Figure 1, a level timer control relay shown generally at 157, and the drive motor 38 as shown in Figures 1 and 5.

The structure of each of the three timers is identical as shown schematically in Figure 5, and a typical timer structure is shown in detail in Figure 6. Referring to Figure 6 each of these timers includes a synchronous timing motor 158 which is adapted to drive a shaft 159, spur gears 160, a shaft 161 and a toothed clutch plate 162. A clutch plate 164 is connected through a shaft 165, spur gears 166 and shaft 168 to a time pointer 170. The timer is provided with a control knob 174 carrying a time set pointer 172 which is movable independently of the pointer 170 and carries a stop member 173 and may be positioned in any position on the face of the timer by adjustment of the control knob. The shaft 168 urges the time pointer 170 against the stop member 173 as a result of the urging of spring 176 which is mounted with one end connected to the shaft 168 and with its other end rigidly affixed to a stationary post 178 which is affixed to the frame 179 of the timer.

A clutch solenoid 180 is provided with an armature 182 on which there is mounted two contact arms 205' and 206' which are adapted to move with the armature 182. Also connected to the armature 182 is a clutch operating lever 186 having a forked outer end 187 which engages the shaft 161, the shaft being rotatable therein and movable thereby for the purpose of providing engagement or disengagement of the clutch plates 162 and 164.

A terminal block 188 is provided with terminals, not visible in Figure 6, for the external connection of lead wires as indicated by the numerals 206, 207, 208 and 209 in each of the timers shown in Figure 5. The terminal 207 is connected to a stationary contact 207', the terminal 208 is connected to the stationary contact 208', the terminal 206 is connected to the contact arm 206' by means of a flexible wire lead 213, and the terminal 209 is connected to one side of the solenoid coil 180 by wiring not shown in Figure 6.

A terminal block 190 is provided on its front face with terminals for the external connection of lead wires as indicated at 201, 202, 203, 204 and 205 in the timers shown in Figure 5. Mounted to the rear of the terminal block 190 is a switch assembly indicated generally at 192. This switch assembly is operated by a tripping arm 194 when the arm is rotated by a tripping pin 196 which engages the arm when the gears 166 and the time pointer 170 have rotated to a zero or vertical position. The upper end of the tripping arm engages a switch arm 198 mounted on the terminal block 190 and to which are affixed two contact members 201' and 204'. Also affixed to the terminal

block 190 are members mounting three contacts 202'', 203' and 205''. The contacts 201', 204', 202'', 203' and 205'' are electrically connected through the terminal block 190 to the terminals 201, 204, 202, 203 and 205, respectively. During operation of the timer, as will be hereinafter described in connection with the circuit diagram shown in Figure 5, the switch assembly 192 will in one position provide contact between contacts 201' and 202'', and between 203' and 204'. In the other position of the switch assembly 192, the contacts 201' and 202', and 203' and 204' will be open, and the contacts 204' and 205'' will be closed.

The terminal 202 is also electrically connected to the depending arm mounting contact 202' which is adapted to be engaged by the contact on the arm 206' when the solenoid 180 is energized. The contact arm 205' is connected to the contact arm 205'' by the flexible conductor 211 and the contact points on the arm 205' are adapted to engage the contact 208' when the solenoid 180 is energized and to engage the contact 207' when the solenoid is deenergized. The timing motor 158 is connected to the terminals 209 and 208, and the solenoid coil 180 is connected to the terminals 201 and 209. These connections, being clearly shown in Figure 5, are for purposes of clarity omitted from Figure 6.

When the timer is in a "reset" position, the time set pointer 172 is manually positioned on the dial of the timer at a distance from the zero point on the dial equivalent to the time of the desired operation of the timer, and the time pointer 170 is held in an identical position and against the time set pointer stop 173 by the action of the spring 176, the clutch plates 162 and 164 being disengaged.

Upon initiation of the timer "timing cycle" 40 operation by an external switch which will be hereinafter described, the solenoid coil 180 is energized, closing the contacts 202'-206' and 205'-208', opening the contact 205'-207' and engaging the clutch plates 162 and 164. The timing motor 158 is energized and will then drive the time pointer 170 toward the zero position against the urging of the spring 176 and move the trip pin 196 toward the tripping arm. When the time pointer reaches the zero position, the trip pin engages the tripping arm to operate the snap action switch and open the contacts 204'-205' and 201'-202'', close the contacts 203'-204' and interrupt the synchronous motor operation as will be hereinafter described in connection with the electrical circuit. The timer is now in a "timed-out" position.

To "reset" the timer for the next sequence of operation, it is necessary that the solenoid coil be deenergized by external control means. De-energizing the solenoid coil opens contacts 202'-206' and 205'-208', closes contacts 205'-207', disengages the clutch 162-164 and permits the spring 176 to return the time pointer 170 to an at rest position against the time set pointer stop 173. The trip pin 196 is thereby moved out of engagement with the tripping arm 194 and the snap action switch operates to close contacts 204'-205'' and 201'-202'' and open the contacts 203'-204'.

The operation of the motor control circuit, shown in Figure 5, may now be described. Assuming the platforms to be in a horizontal position, as shown in Figure 1, the limit switches will be in a corresponding horizontal or central position against the control rod 96 with the level limit

switch 92 actuated as shown in Figure 5. The operator will first close the switch 116 which is mounted on the far side of the box 114 in Figure 1, thus energizing the control circuit from the power line 115.

When the switch 116 is closed with the table in the level position, the control circuit will start to operate immediately and it is unnecessary to depress the start switch 156. The start switch 156, as will be hereinafter described, is provided, when it is necessary, to start the apparatus when the platforms are in such a position that none of the limit switches is energized.

When the switch 116 is closed, the bottom timer cut-out relay coil 227 is energized by current flowing through lines 220 and 226 to the coil, and from the coil 227 through line 228, through terminal 205, contact 204' and terminal 204 in the top timer 120, through conductors 230 and 232 to bottom limit switch 94, through the contact arm 235 of the level limit switch to the power line 234. When the coil 227 of the level timer cut-out relay 157 is energized, the contact arm 229 closes, connecting conductor 238 to conductor 240.

The level timer 122 is energized by current flowing from power line 234 through line 236, contact arm 237 of the level limit switch 92, conductor 238, contact arm 229 of the level timer contact relay, conductor 240, terminal 201 of the level timer to the conductor 214 to the solenoid coil 180 of the level timer relay, and from the solenoid coil 180 through conductor 210, terminal 209, conductors 242, 244, start switch 156 and conductor 246 to power line 220.

When the level timer solenoid coil 180 is energized, the level timer contacts 206' and 205' are drawn into engagement with the connections to level timer terminals 202 and 208, whereupon the level timer timing motor 158 is energized from terminal 209 which is connected to power line 220, as previously described, and through line 212 connected to terminal 208, contact 205', contact 204', terminal 204, conductor 248, top limit switch contact arm 233, conductor 232, bottom limit switch contact 235 to power line 234. At the same time that the level timer timing motor 158 is energized, the level timer pilot light 123 is energized by connection with the level timer terminals 209 and 208, through conductors 242 and 243, respectively, in parallel with the level timer timing motor 158.

The level timer timing motor will operate for a "timing cycle" depending upon the setting of the level timer time set pointer 172 as previously described. Upon the expiration of this time interval, the timer snap action switch will operate and actuate the timer contacts 201' and 204' putting the timer in a "timed-out" position as previously described.

With the level timer in the "timed-out" position, the platforms' drive motor 38 is energized to run in an "up" direction through the following connections: Power from the line 234 will flow through the contact arm 235 of the bottom limit switch 94, conductor 232, the contact arm 233 of the top limit switch 90, conductor 243 to terminal 204 of the level timer 122, through the level timer contact 234' which, with the timer in the timed-out position, closes the circuit between terminal 204 and 203, the current flow passes from terminal 203 through conductor 222 to the "up" terminal 221 of the drive motor 38. The center connection 223 of the motor 38 is connected directly to power line 220.

The motor 38 has the leads from its windings 75

connected to the terminals 221, 223 and 225. The motor windings are so arranged that, when power is applied to the motor terminals 221 and 223, the motor will operate in an "up" direction, i. e., it will operate to drive the platforms 44 and 50 upwardly. When power is applied to the terminal 223 and 225, the motor will operate in a "down" direction, i. e., in a direction which will move the platforms 44 and 50 downwardly.

10 When the level timer 122 assumes the "timed-out" position and the contact 204' has operated to close the circuit between terminal 203 and 204, the timer motor 158 and the level timer pilot light 123 will be deenergized by the opening of the circuit between terminal 203 and terminal 204 as a result of the operation of the contact 204'.

As the drive motor 38 proceeds to move the platforms 44 and 50 in an upward direction, the control rod 96 is moved, the level limit switch 92 actuated as the notch 160 in the rod 96 is moved out from beneath the roller 93 of the level limit switch, and the connection between conductor 238 and 232 is broken by movement of the contact 237 of the level limit switch to a position closing the circuits between lines 236 and 239.

The drive motor continues to operate in an up direction being connected through level timer terminal 203, contact 204', terminal 204, line 248, top limit switch contact 233, conductor 232, bottom limit switch contact 235, to power line 234. The level timer solenoid coil 180 remains energized by its connection with level timer contact 209 and conductor 214, terminal 201, 202, contact 206', 206, conductor 248 through top limit switch contact 233, conductor 232, bottom limit switch contact 235 to conductor 234.

The lower timer thus remains in a "timed-out" position, and the drive motor 38 proceeds to operate in an upward direction until the top limit cam 168 on the control rod 96 engages the roller 91 of the top limit switch 90 and operates the top limit switch contact arm 233 breaking the circuit between lines 232 and 248 and closing the circuit between lines 232 and 250.

45 Operation of the top limit switch opens the circuit connecting the drive motor "up" terminal 221 to power, thereby stopping the up operation of the motor. Operation of the top limit switch 90 also deenergizes the level timer solenoid coil 180 and permits the level timer to assume a "reset" position. Operation of the top limit switch energizes the top timer 120 solenoid coil 180 by completing the connection from the solenoid coil 180 through line 214, terminal 201, line 250, top limit switch contact 233, conductor 232, bottom limit switch contact 235 to the power line 234. When the timer solenoid 180 is energized, the top timer contacts 206' and 205' are actuated and energize the top timing motor 158 and the top timer pilot light 121 by completing the circuit from terminal 208 through contact 205', contact 204', terminal 204, conductor 230, bottom limit switch contact 235 to power. The top timer is now in its "timing cycle." The drive motor 38 is not operative, and the platforms are in a uppermost position as shown at 44' and 50' in Figure 2.

The degree of elevation of the platforms will depend upon the placement of the top limit switch stop cam 168 on the control rod 96. The period of dwell of the platforms in their uppermost positions will depend upon the setting of the top timer time set pointer 172 as previously described.

When the top timer "times-out," the contact

11

204' is operated, opening the circuit between terminals 204 and 205 and closing the circuit between terminals 204 and 203. The top timer timing motor and pilot light, and the level timer cut-out relay coil 227 are deenergized by the 5 operation of the contact 204'.

The down terminal 225 of the drive motor 38 is energized by connection through terminal 203, contact 204', terminal 204, conductors 230, 232, bottom limit switch contact 235 to power line 234.

After a period of motor operation, the top limit switch 90 opens. The top timer solenoid coil 180 remains energized by connection with terminal 209 and by connection through conductor 214, terminal 201, 202, contact arm 206', terminal 206, conductors 230 and 232, bottom limit switch contact 235 and power line 234.

After further operation of the motor, the level limit switch 92 operates as a result of the level limit switch roller 93 engaging the notch 100 in the control rod 96. This actuation of the limit switch opens the circuit between conductors 236 and 239, and closes the circuit between conductors 236 and 238. The level timer cut-out relay contact 229 is open at this time, the coil 227 being deenergized as previously described, therefore, the level timer is not energized. After a further period of operation of the drive motor 38, the level timer limit switch is again actuated as the roller 93 moves out of the notch 100, the 30 contact is reestablished between conductors 236 and 239 by the limit switch contact 237.

After further period of operation by the drive motor in a downward direction, the bottom limit cam 104 engages the roller 95 of the bottom limit switch 94, and the bottom limit switch contact 235 opens the circuit between conductors 234 and 232, and closes the circuit between conductors 234 and 260. Opening of the circuit between conductors 234 and 232 deenergizes the 35 drive motor down connection, stopping the drive motor and deenergizing the top timer solenoid coil 180, permitting the top timer to "reset."

Operation of the bottom limit switch 94 energizes the bottom timer 124 solenoid coil 180 by connecting the coil 180 through conductor 214, terminal 201, conductor 260 and bottom limit switch contact 235 with the power line 234. The other side of the coil 180 is connected to terminal 209 which is energized through conductor 244, switch 156 and conductor 246.

When the bottom timer solenoid coil is energized, the bottom timer contacts 206' and 205' are actuated, and the bottom timer motor 158 and the bottom timer pilot light 125 are energized from line 244, and through line 262, terminal 208, contact 205', contact 204', terminal 204, conductor 239, level limit switch contact 237 and conductor 236 to power. The bottom timer is now in its "timing cycle" and the tables are at rest in a bottom position. The degree of depression of the platforms depends upon the setting of the bottom limit cam 104 on the control rod 96, and the platforms remain at rest in this position for a time depending upon the setting of the bottom timer time set pointer.

At the end of the bottom limit timer "timing period," the contact 204' is operated and the timer assumes a "timed-out" position. Operation of the contact 204' deenergizes the timing motor and the timing motor pilot light by opening the connection to line 239 which is connected to power through the level limit switch 92, and energizes the drive motor up terminal 221 by

12

connecting it through conductor 222, terminal 203 and contact 204' to power.

The drive motor 38 is now operating in an up direction, and after a period of operation, the bottom limit switch 94 operates as it leaves the bottom limit cam 104. The bottom timer solenoid coil 180 remains energized by connection with power through conductor 214, contact 206', terminal 206, conductor 239 and the level limit switch 92.

Operation of the lower limit switch 94 completes the circuit connecting the level timer cut-out relay coil 227 through conductor 228, contact 204' of the top timer 120, conductor 230 and 232 and bottom limit switch contact 235 to power.

The drive motor continues to operate in an upward direction until the level limit switch 92 is again actuated by virtue of the movement of the roller 93 into the notch 100 of the control rod 96. Operation of the level limit switch opens the circuit connecting the drive motor "up" terminal 221 to power through contact 204' of the bottom timer 124, conductor 239 and the level limit switch contact 237. Operation of the level limit switch also deenergizes the bottom timer solenoid coil 180 causing the bottom timer to assume a "reset" position.

Closure of the circuit between conductors 236 and 238 by the level limit switch contact 237 energizes the level timer 122 solenoid coil 180 through the level timer cut-out relay contact 229. The level timer proceeds to effect a timing cycle identical to that hereinbefore described. The operation of the control circuit continues as has been described, each of the timers operating in succession.

When it is desired to terminate the operation of the exerciser, the switch 116 is opened, immediately deenergizing the drive motor and the entire 40 control circuit.

In the sequence of operations previously described, it was assumed that the tables were in a horizontal position when the switch 116 was closed. If the control circuit is deenergized when the tables are in a position in which any of the limit switches are actuated, closing of the switch 116 will result in the timer associated with the actuated limit switch immediately beginning its timing cycle, and the previously described sequence of operation will start from that point in the sequence.

If the control circuit is deenergized when the tables are in a position with none of the limit switches actuated, then, in order to reestablish operation of the control circuit, it is necessary to close the switch 116 and depress the start switch 156. Closure of the start switch 156 will energize the top timer solenoid coil 180 which then locks in through its own contact 205', as previously described, and at the termination of the top timer timing period, the drive motor 36 will operate in a downward direction until the bottom limit switch is actuated and the control sequence continues as previously described.

65 The apparatus disclosed herein provides an exerciser having a high degree of mobility and which may be readily moved from one bed to another in a hospital. The exerciser is adjustable in height so that it may be adjusted for use with beds of different heights and, by means of the flexible straps 17, the exerciser may be snugly attached to either side of a bed.

As previously described, the limits of upward and downward motion of the exerciser may be 75 independently adjusted, and the periods of dwell

in the bottom, level or top positions may be independently adjusted. These adjustments may be readily made to accommodate the needs of any particular patient in accordance with a doctor's prescription. In the normal operation of the exerciser, the platforms will come to rest in the horizontal position only during upward travel of the platforms.

It will be apparent that the platform 16 and the cushion 18, which support the patient's body, may be provided with a hinged portion serving as an elevated back rest which may be adjusted to a position adjacent to that of an adjustable hospital bed on which the patient may be lying. This provision is desirable under some circumstances where it is required that the elevated limb be not raised above the patient's head.

As has been previously described, the platforms 44 and 50 are more narrow than the platform 16 and its cushion 18. Thus, when the exerciser is in operation in its position adjacent to a bed, with the platforms 44 and 50 rising and lowering and the platform 50 moving outwardly and inwardly from the platform 44, there is no contact between the platforms 44 and 50 with the bed mattress or covers which would cause wear on both the bed mattress and covers, and on the covering of the platforms 44 and 50. This clearance between the platforms 44 and 50 and the bed could also be accomplished in an exerciser in which all of the platforms and cushions were of the same width by extending the pads 15 outwardly from the exerciser. This arrangement, however, would have the disadvantage of leaving a space between the bed mattress and the cushion 18 which might prove uncomfortable to the patient.

These and other modifications may be made to the structure of the embodiment of the invention disclosed herein without departing from the scope of the invention as set forth in the following claims.

What is claimed is:

1. An exerciser for elevating and depressing a patient's limb comprising a framework, a platform mounted on said framework for supporting the patient's body, a second platform for supporting the patient's leg, means mounting the second platform for movement in hinged relation with respect to the first mentioned platform, a third platform for supporting the patient's foot, means mounting the third platform for movement away from and toward the second platform, means for moving the second platform upwardly and downwardly in hinged relation to the first mentioned platform, and means for moving the third platform outwardly with respect to the second platform when the second platform is moved upwardly and inwardly with respect to the second platform when the second platform is moved downwardly.

2. An exerciser for elevating and depressing a patient's limb comprising a framework, a platform mounted on said framework for supporting the patient's body, a second platform for supporting the patient's leg, means mounting the second platform for movement in hinged relation with respect to the first mentioned platform, a third platform for supporting the patient's foot, means mounting the third platform for movement away from and toward the second platform, controllable means for moving the second platform upwardly and downwardly in hinged relation to the first mentioned platform, and adjustable means for moving the third platform outwardly

with respect to the second platform when the second platform is moved upwardly and inwardly with respect to the second platform when the second platform is moved downwardly.

3. An exerciser for elevating and depressing a patient's limb comprising a portable framework, a platform mounted on said framework for supporting the patient's body, means mounted on said framework for adjusting the height of the platform, means mounted on said framework for securing the exerciser in position against a bed, a second platform for supporting the patient's leg means mounting the second platform for movement in hinged relation with respect to the first mentioned platform, a third platform for supporting the patient's foot, means mounting the third platform for movement away from and toward the second platform, controllable means for moving the second platform upwardly and downwardly in hinged relation to the first mentioned platform, and adjustable means for moving the third platform outwardly with respect to the second platform when the second platform is moved upwardly and inwardly with respect to the second platform when the second platform is moved downwardly.

4. An exerciser for elevating and depressing a patient's limb comprising a framework, a platform mounted on said framework for supporting the patient's body, a second platform for supporting the patient's leg, means mounting the second platform for movement in hinged relation with respect to the first mentioned platform, means for moving the second platform upwardly and downwardly in hinged relation to the first mentioned platform, a third platform for supporting the patient's foot, and means mounting the third platform for movement away from and toward the second platform, the last mentioned means comprising a linkage including a link pivotally attached to the means for moving the second platform upwardly and downwardly.

5. An exerciser for elevating and depressing a patient's limb comprising a framework, a platform mounted on said framework for supporting the patient's body, a second platform for supporting the patient's leg, means mounting the second platform for movement in hinged relation with respect to the first mentioned platform, means for moving the second platform upwardly and downwardly in hinged relation to the first mentioned platform, a third platform for supporting the patient's foot, and means mounting the third platform for movement away from and toward the second platform, the last mentioned means comprising a linkage connected to the third platform, the framework and the means for moving the second platform.

6. An exerciser for elevating and depressing a patient's limb comprising a framework, a platform mounted on said framework for supporting the patient's body, a second platform for supporting the patient's leg, means mounting the second platform for movement in hinged relation with respect to the first mentioned platform, a third platform for supporting the patient's foot, means mounting the third platform for movement away from and toward the second platform, means for moving the second platform upwardly and downwardly in hinged relation to the first mentioned platform, the last mentioned means comprising a reversible motor, a threaded shaft rotatably driven by the motor, means mounted for movement along the threaded shaft when the shaft is rotated, means attached to the second platform

15

and in engagement with the means mounted on the threaded shaft for moving the second platform as the shaft is rotated, and means moving the third platform with respect to the second platform, the last mentioned means comprising a linkage including a link pivotally attached to the means attached to the second platform.

7. An exerciser for elevating and depressing a patient's limb comprising a framework, a platform mounted on said framework for supporting the patient's body, a second platform for supporting the patient's leg, means mounting the second platform for movement in hinged relation with respect to the first mentioned platform, a third platform for supporting the patient's foot, means mounting the third platform for movement away from and toward the second platform, means for moving the second platform upwardly and downwardly in hinged relation to the first mentioned platform, the last mentioned means comprising a reversible motor, a threaded shaft rotatably driven by the motor, means mounted for movement along the threaded shaft when the shaft is rotated, means attached to the second platform and in engagement with the means mounted on the threaded shaft for moving the second platform as the shaft is rotated, and means moving the third platform outwardly with respect to the second platform when the second platform is moved upwardly and inwardly with respect to the second platform when the second platform is moved downwardly, the last mentioned means comprising a linkage connected to the third platform and connected to the framework, and including a link pivotally attached to the means for moving the second platform upwardly and downwardly.

8. An exerciser for elevating and depressing a patient's limb comprising a framework, a platform mounted on said framework for supporting the patient's body, a second platform for supporting the patient's leg, means mounting the second platform for movement in hinged relation with respect to the first mentioned platform, a third platform for supporting the patient's foot, means mounting the third platform for movement away from and toward the second platform, means for moving the second platform upwardly to a predetermined elevated position and downwardly to a predetermined depressed position in hinged relation to the first mentioned platform, the last mentioned means comprising a reversible motor, a threaded shaft rotatably driven by the motor, means mounted for movement along the threaded shaft when the shaft is rotated, means attached to the second platform and in engagement with the means mounted on the threaded shaft for moving the second platform as the shaft is rotated, and means moving the third platform with respect to the second platform, the last mentioned means comprising a linkage including a link pivotally attached to the means attached to the second platform.

9. An exerciser for elevating and depressing a patient's limb comprising a framework, a platform mounted on said framework for supporting the patient's body, a second platform for supporting the patient's leg, means mounting the second platform for movement in hinged relation with respect to the first mentioned platform, a third platform for supporting the patient's foot, means mounting the third platform for movement away from and toward the second platform, means for moving the second platform upwardly to an elevated position and downwardly

16

to a depressed position in hinged relation to the first mentioned platform, the last mentioned means comprising a reversible motor, a threaded shaft rotatably driven by the motor, means mounted for movement along the threaded shaft when the shaft is rotated, means attached to the second platform and in engagement with the means mounted on the threaded shaft for moving the second platform as the shaft is rotated, means for establishing a period of dwell of the second platform at each of the positions, and means moving the third platform with respect to the second platform, the last mentioned means comprising a linkage including a link pivotally attached to the means attached to the second platform.

10. An exerciser for elevating and depressing a patient's limb comprising a portable framework, a platform mounted on said framework for supporting the patient's body, means mounted on said framework for adjusting the height of the platform, means mounted on said framework for securing the exerciser in position against either side of a bed, a second platform for supporting the patient's leg, means mounting the second platform for movement in hinged relation with respect to the first mentioned platform, a third platform for supporting the patient's foot, means mounting the third platform for movement away from and toward the second platform, controllable means for moving the second platform upwardly and downwardly in hinged relation to the first mentioned platform, and adjustable means for moving the third platform outwardly with respect to the second platform when the second platform is moved upwardly and inwardly with respect to the second platform when the second platform is moved downwardly.

11. An exerciser for elevating and depressing a patient's limb comprising a portable framework, a platform mounted on said framework for supporting the patient's body, means mounted on said framework for adjusting the height of the platform, means mounted on said framework for securing the exerciser in position against either side of a bed, a second platform for supporting the patient's leg, means mounting the second platform for movement in hinged relation with respect to the first mentioned platform, a third platform for supporting the patient's foot, means mounting the third platform for movement away from and toward the second platform, controllable means for moving the second platform upwardly and downwardly in hinged relation to the first mentioned platform, and adjustable means for moving the third platform outwardly with respect to the second platform when the second platform is moved upwardly, and inwardly with respect to the second platform when the second platform is moved downwardly, the second and third platforms being of lesser width than the first mentioned platforms to protect the bed covering against abrasion during operation of the exerciser.

12. An exerciser for elevating and depressing a patient's limb comprising a portable framework, a platform mounted on said framework for supporting the patient's body, means for adjusting the height of the platform, means for securing the exerciser in position against a bed, said securing means including a pair of straps, means for joining said straps to the bed and means for tensioning the straps, a second platform for supporting the patient's leg, means

mounting the second platform for movement upwardly and downwardly with respect to the first mentioned platform, and means for moving the second platform upwardly and downwardly with respect to the first mentioned platform, the exerciser being adapted to support a portion of the patient's body while the patient's limb is being exercised, the remaining portion of the patient's body being supported by the bed.

13. An exerciser for elevating and depressing a patient's leg comprising a framework, a first platform mounted on said framework for supporting the patient's body, a second platform for supporting the patient's leg, means mounting the second platform for movement upwardly and downwardly with respect to the first platform, and devices automatically operative to provide repeated cycles of movements of said second platform, said devices including means for driving the second platform upwardly and downwardly, means for effecting movement of the second platform by said driving means upwardly from an intermediate first position to a second position in which it is located above the first platform, means for interrupting drive of the second platform by said driving means at the end of said movement to provide a dwell of the second platform in said second position, means for effecting movement of the second platform by said driving means at the end of said dwell from said second position to a third position in which it is located below the first platform, means for interrupting drive of the second platform by said driving means at the end of the last mentioned movement to provide a dwell of the second platform in said third position, means for effecting movement of the second platform by said driving means at the end of the last mentioned dwell from said third position to said first position, and means for interrupting drive of the second platform by said driving means at the end of the last mentioned movement to provide a dwell of the second platform in said first position.

14. An exerciser for elevating and depressing a patient's leg comprising a framework, a first platform mounted on said framework for supporting the patient's body, a second platform for supporting the patient's leg, means mounting the second platform for movement upwardly and downwardly with respect to the first platform, and devices automatically operative to provide repeated cycles of movements of said second platform, said devices including means for driving the second platform upwardly and downwardly, means for effecting movement of the second platform by said driving means upwardly from an intermediate first position to a second position in which it is located above the first platform, means for interrupting drive of the second platform by said driving means at the end of said movement to provide a dwell of the second platform in said second position, means for effecting movement of the second platform by said driving means at the end of said dwell from said second position to a third position in which it is located below the first platform, means for interrupting drive of the second platform by said driving means at the end of the last mentioned movement to provide a dwell of the second platform in said third position, means for effecting movement of the second platform by said driving means at the end of the last mentioned dwell from said third position to said first position, and means for interrupting drive of the second platform by said

driving means at the end of the last mentioned movement to provide a dwell of the second platform in said first position, said means for effecting movements of the second platform being independently adjustable to provide various periods of said dwells.

15. An exerciser for elevating and depressing a patient's leg comprising a framework, a first platform mounted on said framework for supporting the patient's body, a second platform for supporting the patient's leg, means mounting the second platform for movement upwardly and downwardly with respect to the first platform, and devices automatically operative to provide repeated cycles of movements of said second platform, said devices including means for driving the second platform upwardly and downwardly, means for effecting movement of the second platform by said driving means upwardly from an intermediate first position to a second position in which it is located above the first platform, means for interrupting drive of the second platform by said driving means at the end of said movement to provide a dwell of the second platform in said second position, means for effecting movement of the second platform by said driving means at the end of said dwell from said second position to a third position in which it is located below the first platform, means for interrupting drive of the second platform by said driving means at the end of the last mentioned movement to provide a dwell of the second platform in said third position, means for effecting movement of the second platform by said driving means at the end of the last mentioned dwell from said third position to said first position, and means for interrupting drive of the second platform by said driving means at the end of the last mentioned movement to provide a dwell of the second platform in said first position, at least one of said means for effecting movements of the second platform being adjustable to provide variation of the dwell preceding the movement effected thereby.

16. An exerciser for elevating and depressing a patient's leg comprising a framework, a first platform mounted on said framework for supporting the patient's body, a second platform for supporting the patient's leg, means mounting the second platform for movement upwardly and downwardly with respect to the first platform, and devices automatically operative to provide repeated cycles of movements of said second platform, said devices including means for driving the second platform upwardly and downwardly, means for effecting movement of the second platform by said driving means upwardly from an intermediate first position to a second position in which it is located above the first platform, means for interrupting drive of the second platform by said driving means at the end of said movement to provide a dwell of the second platform in said second position, means for effecting movement of the second platform by said driving means at the end of said dwell from said second position to a third position in which it is located below the first platform, means for interrupting drive of the second platform by said driving means at the end of the last mentioned movement to provide a dwell of the second platform in said third position, means for effecting movement of the second platform by said driving means at the end of the last mentioned dwell from said third position to said first position, and means for interrupting drive of the second platform by said driving

means at the end of the last mentioned movement to provide a dwell of the second platform in said first position, and means for adjusting the second position of the second platform.

17. An exerciser for elevating and depressing a patient's leg comprising a framework, a first platform mounted on said framework for supporting the patient's body, a second platform for supporting the patient's leg, means mounting the second platform for movement upwardly and downwardly with respect to the first platform, devices automatically operative to provide repeated cycles of movements of said second platform, said devices including means for driving the second platform upwardly and downwardly, means for effecting movement of the second platform by said driving means upwardly from an intermediate first position to a second position in which it is located above the first platform, means for interrupting drive of the second platform by said driving means at the end of said movement to provide a dwell of the second platform in said second position, means for effecting movement of the second platform by said driving means at the end of said dwell from said second position to a third position in which it is located below the first platform, means for interrupting drive of the second platform by said driving means at the end of the last mentioned movement to provide a dwell of the second platform in said third position, means for effecting movement of the second platform by said driving means at the end of the last mentioned dwell from said third position to said first position, and means for adjusting the third position of the second platform.

18. An exerciser for elevating and depressing a patient's leg comprising a framework, a first platform mounted on said framework for supporting the patient's body, a second platform for supporting the patient's leg, means mounting the second platform for movement upwardly and downwardly with respect to the first platform, devices automatically operative to provide repeated cycles of movements of said second platform, said devices including means for driving the second platform upwardly and downwardly, means for effecting movement of the second platform by said driving means upwardly from an intermediate first position to a second position in which it is located above the first platform, means for interrupting drive of the second platform by said driving means at the end of said movement to provide a dwell of the second platform in said second position, means for effecting movement of the second platform by said driving means at the end of said dwell from said second position to a third position in which it is located below the first platform, means for interrupting drive of the second platform by said driving means at the end of the last mentioned movement to provide a dwell of the second platform in said third position, means for effecting movement of the second platform by said driving means at the end of the last mentioned dwell from said third position to said first position, and means for adjusting the second and third positions of the second platform.

19. An exerciser for elevating and depressing a patient's leg comprising a framework, a first platform mounted on said framework for supporting the patient's body, a second platform for supporting the patient's leg, means mounting the second platform for movement upwardly and downwardly with respect to the first platform, and devices automatically operative to provide repeated cycles of movements of said second platform, said devices including means for driving the second platform upwardly and downwardly, and timing means for effecting intermittent operations of said driving means with periods of dwell between said intermittent operations, said timing means effecting, in each cycle, movement of the second platform by said driving means upwardly from an intermediate first position to a second position in which it is located above the first platform, a dwell of the second platform in said second position, movement of the second platform by said driving means at the end of said dwell from said second position to a third position in which it is located below the first platform, a dwell of the second platform in said third position, movement of the second platform by said driving means at the end of the last mentioned dwell from said third position to said first position, and a dwell of the second platform in said first position.

20. An exerciser for elevating and depressing a patient's leg comprising a framework, a first platform mounted on said framework for supporting the patient's body, a second platform for supporting the patient's leg, means mounting the second platform for movement upwardly and downwardly with respect to the first platform, and devices automatically operative to provide repeated cycles of movements of said second platform, said devices including means for driving the second platform upwardly and downwardly, and timing means for effecting intermittent operations of said driving means with periods of dwell between said intermittent operations, said timing means effecting, in each cycle, movement of the second platform by said driving means upwardly from an intermediate first position to a second position in which it is located above the first platform, a dwell of the second platform in said second position, movement of the second platform by said driving means at the end of said dwell from said second position to a third position in which it is located below the first platform, a dwell of the second platform in said third position, movement of the second platform by said driving means at the end of the last mentioned dwell from said third position to said first position, and a dwell of the second platform in said first position, said timing means being adjustable to provide variation of at least one of said dwells.

21. An exerciser for elevating and depressing a patient's leg comprising a framework, a first platform mounted on said framework for supporting the patient's body, a second platform for supporting the patient's leg, means mounting the second platform for movement upwardly and downwardly with respect to the first platform, and devices automatically operative to provide repeated cycles of movements of said second platform, said devices including means for driving the second platform upwardly and downwardly, and timing means for effecting intermittent operations of said driving means with periods of dwell between said intermittent operations, said timing means effecting, in each cycle, move-

21

ment of the second platform by said driving means upwardly from an intermediate first position to a second position in which it is located above the first platform, a dwell of the second platform in said second position, movement of the second platform by said driving means at the end of said dwell from said second position to a third position in which it is located below the first platform, a dwell of the second platform in said third position, movement of the second platform by said driving means at the end of the last mentioned dwell from said third position to said first position, and a dwell of the second platform in said first position, said timing means being adjustable to provide variations of said dwells.

22. An exerciser for elevating and depressing a patient's leg comprising a framework, a first platform mounted on said framework for supporting the patient's body, a second platform for supporting the patient's leg, means mounting the second platform for movement upwardly and downwardly with respect to the first platform, devices automatically operative to provide repeated cycles of movements of said second platform, said devices including means for driving the second platform upwardly and downwardly, and timing means for effecting intermittent operations of said driving means with periods of dwell between said intermittent operations, said timing means effecting, in each cycle, movement of the second platform by said driving means upwardly from an intermediate first position to a second position in which it is located above the first platform, a dwell of the second platform in said second position, movement of the second platform by said driving means at the end of said dwell from said second position to a third position in which it is located below the first platform, a dwell of the second platform in said third position, movement of the second platform by said driving means at the end of the last mentioned dwell from said third position to said first position, and a dwell of the second platform in said first position, and means for adjusting the second position of the second platform.

23. An exerciser for elevating and depressing a patient's leg comprising a framework, a first platform mounted on said framework for supporting the patient's body, a second platform for supporting the patient's leg, means mounting the second platform for movement upwardly and downwardly with respect to the first platform, devices automatically operative to provide repeated cycles of movements of said second platform, said devices including means for driving the second plat-

22

form upwardly and downwardly, and timing means for effecting intermittent operations of said driving means with periods of dwell between said intermittent operations, said timing means effecting, in each cycle, movement of the second platform by said driving means upwardly from an intermediate first position to a second position in which it is located above the first platform, a dwell of the second platform in said second position, movement of the second platform by said driving means at the end of said dwell from said second position to a third position in which it is located below the first platform, a dwell of the second platform in said third position, movement of the second platform by said driving means at the end of the last mentioned dwell from said third position to said first position, and a dwell of the second platform in said first position, and means for adjusting the third position of the second platform.

24. An exerciser for elevating and depressing a patient's leg comprising a framework, a first platform mounted on said framework for supporting the patient's body, a second platform for supporting the patient's leg, means mounting the second platform for movement upwardly and downwardly with respect to the first platform, devices automatically operative to provide repeated cycles of movements of said second platform, said devices including means for driving the second platform upwardly and downwardly, and timing means for effecting intermittent operations of said driving means with periods of dwell between said intermittent operations, said timing means effecting, in each cycle, movement of the second platform by said driving means upwardly from an intermediate first position to a second position in which it is located above the first platform, a dwell of the second platform in said second position, movement of the second platform by said driving means at the end of said dwell from said second position to a third position in which it is located below the first platform, a dwell of the second platform in said third position, movement of the second platform by said driving means at the end of the last mentioned dwell from said third position to said first position, and a dwell of the second platform in said first position, and means for adjusting the second and third positions of the second platform.
